UNITED STATES PATENT OFFICE.

WILLIAM P. HEALY, OF CHICAGO, ILLINOIS, ASSIGNOR, BY MESNE ASSIGNMENTS, TO WIREBOUNDS PATENTS COMPANY, OF KITTERY, MAINE, A CORPORATION OF MAINE.

ADJUSTABLE BOX-BLANK MACHINE.

1,159,379.

Specification of Letters Patent.

Patented Nov. 9, 1915.

Application filed June 19, 1909. Serial No. 503,116.

To all whom it may concern:

Be it known that I, WILLIAM P. HEALY, a citizen of the United States of America, and resident of Chicago, Cook county, Illinois, have invented a certain new and useful Improvement in Adjustable Box-Blank Machines, of which the following is a specification.

My invention relates to machinery for making cleat-reinforced and wire-bound box blanks. It relates more particularly to machinery for this purpose in which an endless chain work-holder is employed for holding the cleats and veneer in place and passing the same below the staplers to secure the binding wires in place. Such a machine is shown in United States Patent No. 815,197, issued March 13, 1906, and in United States Patent No. 864,955, issued September 3, 1907. I do not, however, limit myself to this particular kind of machine.

The object of my invention is to provide improved means for varying the distance between the spacing blocks on the work-holder of a machine of this general character. It contemplates, therefore, a set of spacing blocks which can be readily lifted out of the work-holder, without disturbing the parts of the latter, and then re-inserted in different positions, thus changing the distance between them to accommodate cleats of different lengths. It also contemplates an endless chain work-holder in which the spacing blocks are adjustable or readily movable to different positions thereon without loosening the bolts of the chains. Heretofore, the adjustment of the spacing blocks on the chains necessitated loosening of the bolts which hold the links together, which made it necessary to lose some time in changing the work-holder for a longer or shorter box blank. With my improvement, however, this operation of changing the machine for a different size of box is very much facilitated. The change is made easily and quickly and without interrupting the operation of the machine for an objectionable period of time.

In the accompanying drawings—Figure 1 is a perspective of a portion of one of the chains of the work-holder shown in said prior Patent #864,955, illustrating adjustable spacing blocks therefor embodying the principles of my invention. Fig. 2 is a perspective of one of the spacing blocks

shown in Fig. 1. Fig. 3 is a perspective of the wedge that holds the spacing block in place, and that serves to separate or space the edges of the veneer. Fig. 4 is a plan of a portion of the chain shown in Fig. 1. Fig. 5 is a cross section on line 5—5. Fig. 6 is a view similar to Fig. 5, showing a different form of my invention. Fig. 7 is a view similar to Fig. 4, showing another form of my invention.

As thus illustrated, the chain A is of the general character disclosed in the said prior patents. The links of said chain are held together by bolts B, which latter also hold the pockets C in place on the side of the chain. By loosening these bolts the pockets C can be adjusted or taken off. Each pocket carries therein a spacing block D of any suitable form or character, so far as its function of spacing the cleats apart is concerned. As a matter of special improvement, however, the inner surfaces of the pockets have vertical grooves c. The blocks D each have a rib d on one side and a groove d' on the other side. A wedge or key d² is adapted to be inserted in the groove d', and in one of the grooves c, as shown. The rib d then engages a groove c at the other side, and the block is thus held in place. The wedge or key d² serves, also, as a means for spacing or separating the edges of the veneer. Should it be desired to change the distance between the blocks D, to accommodate cleats of a different length, the wedges or keys d² are removed and the blocks are shifted to their required positions. Thus the work-holder is changed without loosening the bolts B, and in a comparatively short time.

In Fig. 6 the construction is very much the same, except that the block E is provided with spring actuated members e—e for engaging the grooves c in the pocket. By moving these members together, the same can be disengaged from the said grooves, and the blocks thereby removed upwardly from the pockets. The arrangement is preferably such that the members e hold the blocks securely in place while the chain travels upside down.

In Fig. 7 the block F is very much like the block D, except that it is provided with ribs f—f at each side thereof. These ribs engage the grooves at each side of the pockets with sufficient friction to hold them

in place while the chain is traveling upside down.

The member *e* on block *E*, and the lug *f* on the block *F*, serve to separate or space 5 the edges of the veneer.

- It will be seen that with either form of my invention the spacing blocks are easily and quickly shifted to new positions without the necessity of loosening the bolts *B*.
- 10 In each case the block can be lifted directly upward out of the pocket, and then inserted downward at another point therein. This greatly facilitates the changing of the work-holder for different lengths of cleat. The 15 blocks can be used in any suitable form of work-holder. In any event, however, the devices *d*² or *e* or *f*, or any suitable means, engage the teeth to hold the blocks in different positions.
- 20 When a block falls at the juncture between two pockets, I then use a split or divided block, held part on one pocket and part on the other, by any of the expedients shown for this purpose, in a manner that 25 will be readily understood. The blocks shown can be used on different chains or all on the same chain.

What I claim as my invention is:

1. A box blank machine comprising a 30 traveling work-holder, a row of spacing blocks on said work-holder, and means for holding said blocks a variable distance apart, said means being fixed on said work-holder, each block having a vertical groove, 35 and a device insertible in said groove and engaging said means.

2. A box blank machine comprising a traveling work-holder, a row of spacing blocks on said work-holder, and means for 40 holding said blocks a variable distance apart, said means being fixed on said work-holder, each block having a movable element at the side thereof for engaging said means.

3. A box blank machine comprising a 45 traveling work-holder, a row of spacing blocks on said work-holder, and means for holding said blocks a variable distance apart, said means being fixed on said work-

holder, each block having a vertical groove, and a device insertible in said groove and 50 engaging said means, said work-holder consisting of links and bolts which are not disturbed by the said adjustment of said blocks.

4. A box blank machine comprising a traveling work-holder, a row of spacing 55 blocks on said work-holder, and means for holding said blocks a variable distance apart, said means being fixed on said work-holder, each block having a movable element at the side thereof for engaging said 60 means, said work holder having links and bolts which are not disturbed by said adjustment of said blocks.

5. A box blank machine comprising a traveling work-holder, a row of spacing 65 blocks on said work-holder, and means for holding said blocks a variable distance apart, said means being fixed on said work-holder, each block having a vertical groove, and a device insertible in said groove and 70 engaging said means, said means consisting of a side wall having teeth thereon to hold the blocks in different positions.

6. A box blank machine comprising a traveling work-holder, a row of spacing 75 blocks on said work-holder, and means for holding said blocks a variable distance apart, said means being fixed on said work-holder, each block having a movable element at the side thereof for engaging said 80 means, said means consisting of a side wall having teeth thereon to hold the blocks in different positions.

7. A box blank machine comprising a traveling work-holder, a row of spacing 85 blocks on said work-holder, and means for holding said blocks a variable distance apart, said means being fixed on said work-holder, each block having a device at the side 90 thereof for engaging said means.

Signed by me at Chicago, Illinois, this 14th day of June 1909.

WILLIAM P. HEALY.
